TELEPHONE SYSTEM

Willie Saville and Austin Hugh Williams, Liverpool, England, assignors to Associated Telephone & Telegraph Company, Chicago, Ill., a corporation of Delaware

Application November 22, 1937, Serial No. 175,822
In Great Britain December 7, 1936

9 Claims. (Cl. 179—16)

The present invention relates to improvements in telephone or like impulse sending systems and is more particularly concerned with impulse repeating devices of the type adapted to receive 5 trains of impulses on a storage device and to retransmit them in corrected form to succeeding switches, in some cases after a delay which varies in accordance with the nature of the switching operations to be performed preparatory to their 10 despatch. The invention moreover relates to impulse regenerators of the type in which the registering and transmitting members follow one another conveniently along a circular path. The 15 object of the invention is to provide a means whereby the scope of application of impulse regenerators of this type may be widened and whereby the efficiency of arrangements embodying it may be increased.

According to one feature of the invention in 20 an impulse regenerator of the type wherein a stepping member is moved by incoming impulses away from a co-operating member which moves towards the first member to transmit corresponding regenerated impulses, if the first member is 25 moved a predetermined number of steps away from the second member contact springs are operated to produce suitable circuit changes.

According to another feature of the invention in 20 an impulse regenerator of the type wherein a stepping member is moved by incoming impulses from a co-operating member which moves towards the first member to transmit corresponding regenerated impulses, if the first member is advanced so far ahead of the second member that 25 it cannot satisfactorily operate in response to a further train of impulses contact springs are operated to prevent any further operation of the first member.

A further feature of the invention is that in 40 an impulse regenerator of the type wherein a stepping member is moved by incoming impulses in a circular path away from a co-operating member which moves towards the first member to transmit corresponding regenerated impulses, if 45 the first member is advanced a complete revolution so as to encounter the second member contact springs are operated and the second member is released.

The invention will be better understood from 50 the following description of two methods of carrying it into effect reference being had to the accompanying drawings comprising Figs. 1-4. These should be arranged side by side in pairs to form circuit diagrams of impulse repeaters embodying the invention.

In each case it is assumed that use is made, 5 of a regenerator of the type disclosed in J. W. McClew and C. R. Woodland's application No. 79,830, filed May 15, 1936, and that the repeater is connected up to an outgoing junction which is terminated at the distant end in a finder switch. Retransmission of stored pulses is delayed until 10 a signal is received from the distant exchange to indicate that the finder has found the calling junction on substantially the lines disclosed in Figs. 4 and 5 of our application No. 109,072 filed November 4, 1936. It will be appreciated that if 15 there is sufficient delay in the finding operation the regenerator may become full to capacity and be unable to accept further trains of pulses representing digits dialled.

In the circuit shown in Figs. 1 and 2 the invention has been applied in such a manner that if the regenerator becomes full to capacity the 20 succeeding apparatus taken into use is released. the regenerator is restored to normal and busy tone is returned to the calling path while in the 25 circuit of Figs. 3 and 4 the invention has been applied in such a manner that if necessary a second regenerator is connected up in series, thereby doubling the available storage capacity.

The circuit diagrams as shown are arranged so 30 that on reply of the called party the transmission bridge is removed and the speaking leads are connected straight through to the outgoing junction extending to the distant exchange apparatus. By removal of the dotted connections and the insertion of others which will be described subsequently, the transmission bridge may 35 be retained throughout the connection and on reply of the called party a reversal is repeated to the calling side of the circuit for supervisory or metering purposes.

Considering now the circuit shown in Figs. 1 40 and 2, it will be understood that the signalling arrangements which need to be provided to indicate when the regenerator is full to capacity, that is when forty impulses are stored therein, may comprise simply a modified off-normal spring operating cam on the regenerated mechanism. 45 This is arranged to open the off-normal contacts if the impulse receiving disc is rotated through forty steps away from the position of the sending disc. Since these contacts are also open in the normal position of the mechanism, a discriminating means is provided which comprises contacts on a relay held operated during and for a short interval after each train of received impulses. These arrangements will be better appreciated from the ensuing detailed description. 55

A description will first be given of the functioning of the circuit as shown, that is to say as an outgoing repeater with through switching on relay of the called party. In this case the 5 incoming leads will extend from a battery feeding selector while the outgoing negative and positive leads will connect with a junction.

When the repeater is taken into use, the loop 10 extended across the incoming negative and positive conductors operates relay A which thereupon operates relay B. Relay B at armature *b3* applies a guard earth to the P load and at armature *b5* extends an earth over the negative outgoing junction line to operate the line relay in 15 distant junction line circuit which starts up a finder switch in known manner, the usual cut-off relay contacts to earth on the positive line being omitted from the junction line circuit.

On reception of the first train of impulses, 20 relay A responds and on each release relay B holds operated due to its slug while earth is extended over armatures *a1*, *b1*, *br3* and *rb5* to energise the regenerator receiving magnet RM in order that the digits may be stored. Relay C operates in parallel with the magnet and holds during 25 the train due to its slug. At armature *c1* it brings up relay IP which has no function at this stage, and at armature *c2* it energises the regenerator marking magnet MM.

30 It should be mentioned that the regenerator comprises essentially a receiving ratchet wheel R which is rotated step by step under control of the magnet RM and which is arranged on one side of a fixed disc P carrying around its periphery a row of forty pins. The rotation of the receiving disc R stores up energy in a clockspring to drive the sending disc S and thus actuate the impulse springs IMP and send out regenerated impulses of the correct character. Before the 35 first digit is received the armature of the marking magnet MM is resting on a pin in the disc P which it has pushed forward to restrain the sending disc S. During the first train of pulses the energisation of the marking magnet due to operation of relay C tilts a lever carried by the receiving disc R out of engagement with the pins. At the end of the train the receiving disc will have been rotated a corresponding number of steps and on the release of relay C after a short interval 40 due to its slug, the marking magnet MM is de-energised and thus allows the lever carried by the receiving disc R to tilt back towards the disc P thereby displacing into the path of the disc S a pin corresponding to the digit dialled. 45 Hence if the successive digits dialled are 5, 4 and 7 pins numbers 5, 9 and 16 from the original resting position are displaced. It should be noted that the sending disc S is at present restrained by the pin which was displaced at the end of the 50 previous call.

60 When the receiving disc R is first moved off-normal, the off-normal springs NI close and thus when the marking magnet is restored at the end of the first digit the springs *mm* controlled by this 65 magnet close and a circuit is completed over contacts NI to operate relay BY which thereupon locks by way of armature *by1*. These contacts also complete a circuit over armatures *b2* and *c1* to hold relay IP each time relay C releases.

70 Further trains of incoming pulses are accepted and stored by the regenerator but no retransmission of the stored trains can commence until the distant line finder signals that it has found the calling junction.

75 When this occurs the cut-off relay operates in

the usual manner and switches the junction line through to the distant incoming selector. Relay A in the incoming selector provides a battery connection to the negative line and an earth connection to the positive line as is the usual practice, 5 and as a result relay I in the repeater circuit is now operated by way of resistance YB to the earthed positive line and at armature *i1* it completes an operating circuit for relay SW from the earthed P lead. Relay SW at armature *sw1* locks 10 independently of the armature *i1*, at armatures *sw2* and *sw3* disconnects the battery and earth connections extending to the outgoing negative and positive conductors and substitutes in their place a bridge consisting of the regenerator im- 15 pulse springs IMP and relays D and I which however are now short-circuited by armature *by6*. Armature *sw4* polarises relay D and armature *sw5* completes a circuit from earth, off-normal contacts NI, fixed disc P which is in contact with the 20 pin left projecting from the previous call, the reset pin in the disc S which bears against the displaced pin, contacts *sm*, armatures *by8* and *sw5* to short-circuit relay IP while at armature *sw6* an operating circuit is completed for relay IS 25 in series with the regenerator sending magnet SM, the magnet being non-operative in this condition.

After a short interval relay IP releases and at armature *ip2* disconnects relay IS which holds 30 operated for a further short period due to its short-circuited upper winding. On the release of relay IS a circuit is completed from earth, armatures *ip2*, *by4* and *is3* to energise the sending magnet SM which now pushes the reset pin in the 35 disc S to the right in order to restore the displaced pin in the disc P against which it is resting. On the operation of the magnet SM the contacts *sm* open and thus remove the short-circuit from relay IP which immediately re-operates and at armature *ip2* re-operates relay IS and de-energizes the magnet SM.

As described in J. W. McClew and C. R. Woodland's application No. 79,830, filed May 15, 1936, the reset pin is now withdrawn thus releasing the 45 stop pin displaced at the end of the first digit. During this rotation a fresh train of impulses corresponding in number to those received, but correct as regards ratio and speed, is generated at the springs IMP controlled from the regenerator 50 and these impulses serve to set the switch at the distant exchange. When the reset pin in the disc S comes up against the displaced stop pin indicating the termination of the first series of impulses, relay IP is again short-circuited and in 55 turn releases relay IS to produce another momentary operation of the sending magnet SM. Accordingly the disc S is released to generate a second series of impulses in the manner described. It will be appreciated that the reception and re-transmission of impulses may go on simultaneously but that the two operations are independent of each other and that the sequential release of relays IP and IS in each case provides the necessary pause between successive series of impulses. 60

When all digits received have been retransmitted, the sending disc S will catch up with the receiving disc R, whereupon the off-normal contacts NI open and relays BY, IP and IS are released. Relay BY upon releasing re-inserts re- 70 lays D and I in the outgoing loop.

When the connection is completed and the called subscriber replies, battery is reversed over the called side of the circuit to operate the shunt field relay D which at armature *d1* operates relay 75

RB from the earthed P lead. Relay RB at armature *rb1* locks independently of the armature *c1*, at armatures *rb2* and *rb3* disconnects the transmission bridge thereby releasing relays A and B and also extends the calling side of the circuit straight through to the succeeding switch, at armature *rb4* disconnects the impedance bridge relays D and I from the speaking circuit and at armatures *rb5* and *rb6* disconnects the regenerator receiving magnet RM and marking magnet MM respectively.

On the release of the connection at the end of the conversation, earth is removed from the P conductor by the controlling switch in the train whereupon relay RB releases and the repeater is freed for further use.

Returning now to the point in the description where the distant line finder was set hunting for the calling junction, it will be appreciated that if there is a sufficient delay in finding, the number of impulses received on the regenerator may be in excess of its storage capacity. Assuming now that a total of forty impulses is received and that relay SW still remains unoperated, at the end of the last train of impulses relay A remains operated and relay C commences to release. Since the device is now full to capacity the off-normal contacts *N1* are opened in the manner described earlier and hence during the release time of relay C a circuit is completed at armature *c3* to operate relay BY over its lower winding in series with relay BY, the latter relay remaining operated in this condition. Relay BY at armature *br1* locks over its upper winding, at armature *br2* completes a holding circuit for relay BY which is independent of armature *c3*, at armature *br3* disconnects the impulsing circuit to the regenerator receiving magnet RM and relay C and at armature *br4* prepares a circuit for short-circuiting relay IP. At armature *br5* a busy tone transformer is connected up to the middle winding of relay A on to the incoming speaking conductors in a balanced circuit, while at armatures *br6* and *br8* the battery and earth connections are removed from the outgoing leads thereby opening the start circuit to the finder at the distant exchange. On the release of relay C a circuit is completed at armature *c1* to short-circuit relay IP whereupon the stored digits are retransmitted from the regenerator into an open circuit in readiness for the release of the connection by the calling party.

Should more than forty impulses be received in the above circumstances, the receiving disc R on being rotated forty steps away from the sending disc S is mechanically prevented from rotating further, while relay BY will be operated with the above-described functions.

Owing to the fact that the regenerator receiving magnet RM is operated on the reverse drive principle, there is a tendency for relay BY to operate in series with relay BY in the "break" period of the first impulse of the first train received when relay C and the magnet RM are energized but the *N1* contacts are not closed. Relay C however in addition to completing an operating circuit for relay BY at armature *c3*, also energizes the marking magnet at armature *c2* and this magnet opens the operating circuit of relay BY at contacts *mm*. In order that there will be no possibility of relays BY operating during the operating time of the marking magnet, it is provided with a small armature end slug to render it slow in operating; this slug is however not large enough

to prevent relay BY from operating in a normal manner during the release time of relay C.

Considering now the functioning of the circuit as an outgoing repeater in which the transmission bridge is retained during conversation, the incoming leads will extend from a non-battery feeding selector. The dotted connections are omitted and in their place other connections are made between terminals 3 and 5, 4 and 6 and 8 and 10. With those arrangements the reception and retransmission of the digits takes place in the manner described but when the calling party replies relay RB upon operating repeats the reverse battery conditions to the calling side of the circuit for metering or supervisory purposes.

On the release of the connection at the end of the conversation, relay A releases and is followed by relay B which opens the forward loop at armature *b5* to release the switches in the distant exchange. It will be noticed that relay C is operated during the slow release period of relay B and in turn operates relay IP to maintain earth on the P conductor after the release of relay B. By this means a double guard is provided on the release trunk conductor P to ensure an adequate period for the release of the switches at the distant exchange before the repeater is again freed for further use. In the case where the repeater is adapted for through switching this double guard period would of course be provided from the preceding battery feeding switch.

In case the calling subscriber should release the connection prematurely, that is, by hanging up his receiver during dialling, relay A upon releasing disconnects relay B and operates relay C. Assuming that relay SW has not been operated to initiate retransmission of the stored digits, relay C at armature *c1* maintains relay IP. On the release of relays B, C and IP in turn, an earth is extended over armatures *ip2*, *by4* and *is3* to energize the sending magnet SM whereupon the regenerator commences to retransmit its stored digits into an open circuit, a single pause comprising the release time of relay IP being provided between each digit since the upper winding of relay IS is not now short-circuited at armature *sw6*. When all the digits have been sent relay BY is released at the off-normal contacts *N1*, and at armature *by2* earth is removed from the P conductor to free the repeater for further use.

In case the repeater is functioning in an incoming capacity, the circuit operation will be as previously described, but on a premature release of the connection it will be clearly desirable to guard the distant end of the junction against seizure until the regenerator is fully restored to normal. This is achieved by the extension of earth by way of armatures *b3*, *by7* and *rb2* on to the incoming negative conductor during the period that relay BY remains operated and this serves to operate a relay at the distant outgoing end of the junction to apply guarding conditions thereto.

In case the regenerator fails to retransmit all its stored impulses, relay BY holds operated to the off-normal contacts *N1* and as a result earth is maintained on common conductor 11 extending to delayed alarm equipment.

Referring now to the circuits of Figs. 3 and 4 which employs two regenerators connected in series, arrangements are made whereby the first mechanism on storing its full complement of digits transmits a signal to initiate a switching operation which transfers the succeeding incoming digits to the second mechanism. The stored

digits are subsequently retransmitted in corrected form from each mechanism in proper sequence. In this case a slight modification is required on the first mechanism in that the special 5 cam is arranged to re-open the off-normal contacts when the receiving disc has been rotated from thirty-one to forty steps ahead of the position of the sending disc. This is done since it will be appreciated that when the disc is in any position 10 up to 30 the regenerator can still accept another digit of any value but in position 31 it could not accept a digit comprising ten impulses. A discriminating means is again provided in the form of contact of the C relay so 15 that switching over from the first to the second mechanism occurs only at the termination of the digit which carries the receiving disc into positions 31 to 40.

Since the circuit follows along the same lines 20 as that previously described only the differences in the operation will be referred to in detail.

On the reception of the incoming pulses, relay A responds and steps the receiving magnet RM to store them on the first regenerator. If there 25 is a sufficient delay in finding the calling junction line at the distant exchange, the receiving disc will be carried in response to one of the trains of impulses past position 30. At the end of this train, relays A and B remain operated 30 and relay C commences to release in the usual manner and during its release time earth is extended over armatures c_3 and k_2 to operate relay BR in series with relay BY which remains held. Relay BR upon operating locks up in series 35 with relay BY at armature br_2 and at armature br_1 operates relay K. Relay K thereupon at armature k_1 locks independently of armature br_1 , at armature k_2 disconnects the original operating circuit for relay BR, at armatures k_3 and 40 k_4 connects up circuits to the marking magnet 2MM and the receiving magnet 2RM respectively of the second regenerator and at armature k_5 prepares a circuit for relay CO.

Subsequent trains of incoming pulses are therefore 45 received and stored by the second regenerator.

When the distant line finder finds the calling junction, relay SW operates and initiates the sending out of the stored pulses from the first 50 regenerator in the normal manner by short circuiting relay IP.

When all digits stored therein have been retransmitted, the sending disc S catches up with the receiving disc R whereupon the off-normal 55 contacts N_1 open and restore relay BY, relay BR having been short-circuited and released by these contacts during the sending out. A circuit is now completed over armatures by_2 and k_5 to operate relay CO. Relay CO at armature co_2 connects up the sending magnet 2SM of the second 60 regenerator, at armature co_3 completes a re-operating circuit for relay BY from earth over the second regenerator off-normal contacts $2N_1$ and at armature co_4 completes a circuit to maintain 65 relay IP which will be still holding operated due to its slug in spite of the opening of its original circuit at contacts N_1 . On the re-operation of relay BY, earth is extended over contacts $2N_1$, pin plate 2P, sending disc 2S and 70 sending magnet interrupter contacts 2sm, armatures co_5 , by_8 and sw_5 to short-circuit relay IP. On the release of relay IP the sending out is initiated from the second regenerator which generates at its impulsive contacts 2IMP a fresh 75 set of impulses corresponding to those stored.

If it should be so desired, the second mechanism might be modified in the manner described in conjunction with Figs. 1 and 2 so that busy tone would be returned to the calling party if both mechanisms should become full to capacity. 5

A mechanical impulse repeater modified according to the invention can be advantageously applied in a discriminating selector repeater at a sub-satellite exchange especially where there is a shortage of junctions when it is undesirable to 10 take into use the junctions to the satellite and main offices until the dialling of a plurality of discriminating digits has indicated that it is necessary. Another application is in connection with impulse repeaters which are provided with 15 multi-fee metering facilities in which case digit storage is also necessary until such time as access can be had to the common multi-fee metering equipment.

We claim:

1. In an automatic circuit arrangement for an impulse regenerating device, means for transmitting trains of impulses to said device, marking means in said device stepped in accordance therewith, other stepping means in the device operated to transmit said trains of impulses in accordance with said markings, means for rendering said last means effective responsive to the initial step of said marking means, and means operated responsive to the marking means advancing a predetermined number of steps away from the transmitting means for rendering said first and said third means ineffective. 30

2. In an automatic circuit arrangement, an impulse regenerating device having two stepping members, means for transmitting impulses to the device for causing one of said members to step in accordance therewith, the other of said members operated subsequently to step in accordance with the movement of said one member for transmitting impulses, means for rendering said operation of said other member ineffective, and means for operating said last means responsive to said members becoming separated a predetermined amount. 45

3. In an automatic circuit arrangement, an impulse regenerating device having two stepping members, means for transmitting impulses to the device for causing one of said members to step in accordance therewith, the other of said members operated subsequently to step in accordance with the movement of said one member for transmitting impulses, means for preventing the operation of said one member, and means for operating said last means responsive to said members becoming separated a predetermined amount. 55

4. In an automatic circuit arrangement, an impulse regenerating device having two stepping members, means for transmitting impulses to the device for causing one of said members to step in accordance therewith, the other of said members operated subsequently to step in accordance with the movement of said one member for transmitting impulses, and relay operated responsive to the members becoming separated a predetermined amount for controlling the further operations of the members in said device. 60

5. In an automatic circuit arrangement, an impulse regenerating device having two stepping members, said members having a normal position relative to one another, means for transmitting trains of impulses to the device for causing one of said members to step away from said position in accordance therewith, the other of said members operated in accordance with the stepping of 70 75

said one member to transmit similar trains of impulses, and means operated when said one member has advanced a predetermined number of steps farther than said other member for disabling said first means.

6. In an automatic circuit arrangement, two stepping members, means for transmitting trains of impulses to operate one of said members, control means operated a first time by said one member to prepare the other of said members for operation and a second time by said one member to initiate said operation of said other member, means for at times initiating the operation of said other member before said second operation of the control means, and means for controlling the operation of said other member in accordance with said operation of said first member at said times to cause said other member to transmit trains of impulses similar to said first trains of impulses.

7. In an automatic circuit arrangement including an impulse generating device, an outgoing circuit, means for transmitting trains of impulses to said device, a marking member in said device operated responsive thereto, another member in the device subsequently operative to co-operate therewith and to retransmit said trains of impulses to said outgoing circuit, means operated at times over the outgoing circuit for initiating the operation of said other member, and means operated at other times by said marking member for initiating the operation of said other member.

8. In a circuit combination, an outgoing circuit, two impulse regenerating devices each hav-

ing two mechanically co-operating members, means for transmitting impulse trains to the first of said devices, one member of said first device stepped responsive to certain of said trains, the other member of said first device operated subsequently to step in accordance with said movement of its co-operating member for transmitting impulses to said outgoing circuit, means operated when a certain relative position exists between the members of the first device for causing one member of the second of said devices to step responsive to subsequent trains of impulses transmitted by said first means, and means operated when normality is restored between the members of said first device for causing the operation of the other member of said second device to step in accordance with said movement of its co-operating member for transmitting impulses to said outgoing circuit.

9. In a storage arrangement, two storage devices, means for transmitting trains of impulses, means in the first of said devices for receiving and storing a plurality of said trains of impulses, means operated responsive to the storage of a predetermined total number of impulses in said first device to prepare the second of said devices for operation, and means operated responsive to the first termination of a train of impulses after said preparation of the second device to render said second device effective to receive and store one or more successive trains of said impulses.

WILLIE SAVILLE.
AUSTIN HUGH WILLIAMS.
